UNITED STATES PATENT OFFICE

JOSE F. CARPENTER, OF BRIGHTWOOD, VIRGINIA

METHOD OF ASSEMBLING POULTRY COOPS

Application filed July 15, 1931. Serial No. 550,973.

This invention relates to a method of assembling a poultry coop wherein the manufacture of all of the parts of the coop, except setting it up, are completed in a factory 5 provided with extensive machinery, equipment and expert mechanics, so that such parts of the coop may then be shipped in extremely compact form and at a minimum of transportation expense to be readily assembled by a novice or inexpert person at the destination where the coop is to be used.

In order to understand and appreciate the merit and importance of this invention, it should here be explained that coops must 15 not only be strong and well made according to the specifications insisted upon by the carriers, but they must be extremely cheap in price. This is true to such an extent that most of the coops must be manufactured 20 within a limited radius from the point of use. A coop set up ready for use consumes so much cubic feet of space that the freight charge for transporting coops for any considerable distance makes the cost excessive. 25 Consequently the manufacturers equipped to make the best coops, although they may meet local competition, are unable to ship their coops any great distance because of freight tariffs, with the result that many sections 30 of the country are either equipped with a very poor grade of coop or they must suffer from an excessive cost for coops in which to ship their poultry to the market.

This invention is sought to overcome the difficulties outlined above. The setting up or assembling of a complete coop at the factory is really the work of an extremely expert coop maker. All of this work in the past has been done in factories wherein the method of procedure is to construct the top, this being the portion ordinarily provided with the door; rods, round in cross-section, are then driven into holes formed in the side and end rails of the top, after which the side and end rails, respectively, of the bottom, are then driven onto the opposite ends of the rods by use of what is known as the "touch system" for feeling and guiding the rods into the holes as the driving operation progresses. After the top has been connect-

ed to the side and end rails of the bottom by means of the vertical rods as just described, a plurality of boards are nailed to the bottom rails to form a flooring.

The foregoing is the generally recognized 55 conventional method of assembling a coop at the factory complete and ready for shipment and use. The bottom or flooring is always put on last.

In my invention, and in order to prepare 60 the various parts of a coop as completely as it may be done at the factory and at the same time have these parts so they may be transported disassembled and yet be assembled by one unskilled in that line of work, 65 it has become necessary to reverse entirely the method of procedure, so that, generally stated, the bottom or floor portion is completed first and the assembly process starts with the bottom and ends with the top instead of starting with the top and ending 70 with the bottom portion, in accordance with the old and recognized method of building coops prior to my present invention.

Another advantage of using my method 75 of assembly, whereby the bottom is entirely completed first, is that by thus nailing the floor boards to the bottom frame, an ordinary nailing machine with cleating attachment may be used to bend over and securely cleat 80 the nails to the frame so that the floor boards cannot be removed without leaving evidence of such removal. At the present time shippers are greatly annoyed because flooring of 85 coops is ordinarily not cleated and handlers of poultry sometimes pry loose a floor board, remove some of the poultry from the coop, and replace the board without leaving any evidence of tampering. In this way my 90 method of assembling a coop really results in a stronger and more secure coop than that customarily now produced by most coop factories.

With the foregoing and other objects in 95 view, the invention consists of the new and improved method hereinafter more specifically described, of assembling a poultry coop, but it is to be understood that changes, variations and modifications may be resorted 100

to without departing from the scope of the invention as claimed.

The drawings illustrate various stages in the assembling of a coop in conformity with the method which comprises my invention. Like reference characters denote corresponding parts through the several views.

Figure 1 is a perspective view illustrating the first step in the assembling of the coop, 10 and illustrating also the building of such a coop with reinforcing middle side and end rails, the use of which reinforcing rails is optional.

Figure 2 is a perspective view illustrating the reinforcing middle side and end rails raised to a position adjacent the top of the vertical rods which form the walls, and which constitutes the second step of the 15 method.

Figure 3 is a side elevation illustrating the procedure and initial position in applying one top side rail preliminary to driving the upper ends of the rods into said rail.

Figure 4 is a perspective of the coop after 20 the third step illustrated in Figure 3 has been completed with respect to both of the top side rails.

Figure 5 is a perspective of the fourth step 25 wherein the end top rails, separated from the side top rails, are driven into engagements with the end vertical rods by bending these rods outward slightly and proceeding as illustrated in Figure 3 of the drawings.

Figure 6 is a perspective of the coop showing the fifth step of the method wherein the end top rails, after engagement with the end vertical rods, are moved toward each other and into engagement with the ends of the side 30 top rails as shown.

Figure 7 is a perspective illustrating the 35 finished coop and showing the sixth step of the method which comprises locking the corners together by means of vertical corner rods and nails driven transversely therethrough 40 to bind the unit together.

Figure 8 is a fragmentary perspective view 45 of the bottom and rail.

Figure 9 is a detail in section of a top side 50 rail illustrating how the transverse rods of the top and the vertical rods are inserted into the rail.

Referring to the drawings, the bottom is generally identified by the numeral 1, and the top 2, the vertical side walls by the numeral 3 and the vertical end walls by numeral 4.

The bottom 1 comprises side rails 5, formed with a plurality of spaced holes filled partly transversely therethrough throughout 55 the length of the rail, and formed with a bifurcation 6 at opposite ends thereof. End rails 7 are similarly drilled but with a tenon 8 at its ends adapted to engage with the bifurcation 6 at the ends of the side rails. 60

Holes 9 are drilled through the bifurcation 65

and tenon so as to register when the side and end rails are engaged. The floor 10 is then nailed securely to the side and end rails so that the holes drilled in said rails will be exposed. The work of thus forming the bottom 70 is performed at the factory.

The top 2 is formed of side rails 11 with bifurcations 12 at the ends as in the case of the bottom side rails. End rails 13 are tenoned as at 14 to engage with the bifurcation 75 12 of the side rails. The end rails are formed with slots 18 therethrough adapted to receive tenons 16 formed upon the ends of reinforcing rails 17. Said reinforcing rails 17 are formed with holes 18' transversely therethrough spaced apart so as to register with openings 19 drilled transversely in the side rails 11. Transversely of the top 2 and passing through the holes in the rails 17, and snugly driven into the openings 19 of each 80 of the side rails 11, are a plurality of rods 20 extending entirely across the top member of the coop excepting only the center thereof wherein is left an opening in which a pivoted or hinged door 21 is mounted for ready 85 access to the coop. Horizontally along the underside of the side and end rails 11 and 13 are drilled a plurality of openings spaced apart to register with the openings drilled 90 in the side and end bottom rails 5 and 7, 95 respectively.

The end top rails 13 are fitted into engagement with the side top rails 11 and the reinforcing top rails 17, whereupon holes 22 are 100 drilled through the bifurcated and tenon ends of the engaged rails. The end top rails are thus left in a condition to be readily removable from engagement with the side top rails when it is desired to assemble the coop. 105

A plurality of rods 23, round in cross-section, are prepared for the sides, ends, and corners.

For that type of coop that is to be made especially strong and rigid, reinforcing middle side rails 24 and reinforcing middle end rails 24' are provided with spaced holes drilled transversely therethrough adapted to register with the openings in the bottom and top side and end rails respectively. These reinforcing middle side rails are provided with a cutaway portion at the inner part of their end edges, as at 25 adapted to engage 110 with the ends of the reinforcing middle end rails to form a lock against movement of the reinforcing rails with respect to each other. The reinforcing rails are of less length than the other rails. 115

In shipping the various parts formed and made up as heretofore described, the side and end middle reinforcing rails 24 and 24', together with the vertical rods 23 are placed within the recess formed by the side and end rails of the bottom 1. The top, formed as previously described, is then superposed upon the bottom, formed as previously described, 120 125 130

thus making a receptacle, extremely compact and less than two and one-half inches in height, as compared with a height of about thirteen inches which is the displacement measurement of a completed coop ready for use.

In assembling the coop, pre-formed in the manner and to the extent heretofore described, and the steps of which constitute the invention claimed herein, I first superimpose the side and end middle reinforcing rails 24 and 24' upon the side and end bottom rails 5 and 7 respectively, as shown in Figure 2 of the drawings. I thereupon drive the rods 23 individually through the holes in the reinforcing middle rails 24 and 24' and into the openings 9 formed in the side and end bottom rails, these rods thus assuming a vertical position.

It should be here explained that some coops are made without the reinforcing middle rails 24 and 24'. The method here described applies as well to coops that are assembled without the middle reinforcing rail as those with it. When these reinforcing rails are not used the steps describing its use are simply eliminated from the method of assembling.

The next step is to raise the middle reinforcing rails on the rods to a point adjacent the tops of the vertical rods as illustrated in Figure 2 of the drawings. Since the holes through the reinforcing rods are slightly greater in circumference than the rods, the sliding of the reinforcing rail on the rods is not difficult. However, the openings in the bottom rails as well as the top rails form a snug fit for the vertical rods. Therefore when these rods are driven by means of a mallet or hammer within the openings, they tend to hold fast and are not displaced by moving the middle reinforcing rail upwardly with respect to the vertical rods.

Since the openings in the top side rails register with the holes in the middle reinforcing rails, the movement of the latter toward the top of the vertical rods automatically positions the upper ends of the rods so that there is no difficulty in having the ends of the rods register with the holes in the side and end rails of the top so that by using the set block 26 against which to pound to avoid splitting the rail, engagement of the top with the vertical rods is easily and quickly accomplished. However, before the top is thus driven into engagement with the vertical side rails, the end rails 13 of the top have previously been removed. Otherwise it is not possible to attach the top to the side and end vertical rods.

The end rails 13 are then driven into engagement with the vertical end rods 23 by bending these rods outward slightly to avoid engagement with the ends of the top 2 while the end rails are thus being secured to the

vertical end rods. When the end top rails have been thus secured, the natural spring tension of the rods tends to force the end of the coop thus formed into engagement with the bifurcated ends 12 of the side top rails 70 and the tenons 16 of the reinforcing top rails, as shown by Figure 6.

The next step in the method is to move to a middle position the middle reinforcing rails 24 and 24' in which position they are held by means of a few nails driven transversely therethrough and into several of the vertical rods as indicated at 27 of Figure 7. The corner rods 28 are then driven through the top and bottom side and end rails to secure the same together, this being held in locked position by means of nails 29 driven transversely through the end of the rail and into the corner rods, respectively.

What I claim is:—

1. In a method of assembling a poultry coop of that type including a bottom having its upper face provided with end interengaging side and end rails and a top having end interengaging side and end rails detachably connected together, said rails having spaced means for receiving wall forming rods, driving wall forming rods into said means of the rails on said bottom to form the side and end walls of the coop, disconnecting the end rails 90 of the top from the side rails of the latter, driving one of the top side rails upon the rods forming one side wall, driving the other top side rail upon the rods forming the other side wall, then successively driving the top end rails upon the rods forming the end walls of the coop while such rods are sprung outwardly and then successively connecting the end top rails to the ends of the top side rails.

2. In a method of assembling a poultry coop of that type including a bottom having its upper face provided with end interengaging side and end rails and a top having end interengaging side and end rails detachably connected together, said rails having spaced means for receiving wall forming rods, driving wall forming rods into said means of the rails on said bottom to form the side and end walls of the coop, disconnecting the end rails of the top from the side rails of the latter, driving one of the top side rails upon the rods forming one side wall, driving the other top side rail upon the rods forming the other side wall, then successively driving the top and rails upon the rods forming the end walls of the coop while such rods are sprung outwardly, then successively connecting the end top rails to the ends of the top side rails, and then securing corner posts to the interengaging ends of the top rails and to the interengaging ends of the bottom rails.

3. In a method of assembling a poultry coop of that type including a bottom having its upper face provided with end interengag- 130

ing side and end rails, a top having end interengaging side and end rails detachably connected together and reinforcing rails for each of the walls of the coop, said rails having means for receiving wall forming rods, positioning the reinforcing rails upon the side and end rails on said bottom, driving wall forming rods through said reinforcing rails and into the means of the side and end rails on said bottom to form the side and end walls of the coop, shifting the reinforcing rails upwardly on said driven rods to a position adjacent the upper ends thereof, disconnecting the end rails of the top from the side rails of the latter, driving one of the top side rails upon the rods forming one side wall, driving the other top side rail upon the rods forming the other side wall, then successively driving the top end rails upon the rods forming the end walls while such rods are sprung outwardly, then successively connecting the end top rails to the ends of the side rails, and then shifting the reinforcing rails to a position substantially centrally of said walls.

4. In a method of assembling a poultry coop of that type including a bottom having its upper face provided with end interengaging side and end rails, a top having end interengaging side and end rails detachably connected together and reinforcing rails for each of the walls of the coop, said rails having means for receiving wall forming rods, positioning the reinforcing rails upon the side and end rails on said bottom, driving wall forming rods through said reinforcing rails and into the means of the side and end rails on said bottom to form the side and end walls of the coop, shifting the reinforcing rails upwardly on said driven rods to a position adjacent the upper ends thereof, disconnecting the end rails of the top from the side rails of the latter, driving one of the top side rails upon the rods forming one side wall, driving the other top side rail upon the rods forming the other side wall, then successively driving the top end rails upon the rods forming the end walls while such rods are sprung outwardly, then successively connecting the end top rails to the ends of the side rails, and then shifting the reinforcing rails to a position substantially centrally of said walls, and then securing corner posts to the interengaging ends of the bottom rails.

5. In a method of assembling a poultry coop of that type including a bottom having its upper face provided with side and end rails, a top having side and end rails and reinforcing rails for each of the walls of the coop, the rails being provided with spaced means for receiving wall forming rods, driving wall forming rods into said means of the rails on said bottom to form the side and end rails of the top from the side rails of the latter, successively driving the side rails of the top upon the rods forming the side walls, successively driving the top end rails upon the rods forming the end walls of the coop while such rods are sprung outwardly, and then connecting the top end rails to the top side rails.

upon the rods forming the side walls of the coop, successively driving the end rails of the top upon the rods forming the end walls of the coop while such rods are sprung outwardly, successively securing the end rails of the top to the side rails of the latter, utilizing the reinforcing rails as guides during the driving of the rods into the rails on said bottom and when driving the rails of the top upon said rods, and then positioning said reinforcing rails substantially centrally of the walls of the coop.

6. In a method of assembling a poultry coop of that type including a bottom having its upper face provided with side and end rails, a top having side and end rails and reinforcing rails for each of the walls of the coop, the rails being provided with spaced means for receiving wall forming rods, driving wall forming rods into said means of the rails on said bottom to form the side and end rails of the top from the side rails of the latter, successively driving the side rails of the top upon the rods forming the side walls of the coop, successively driving the end rails of the top upon the rods forming the end walls of the coop while such rods are sprung outwardly, successively securing the end rails of the top to the side walls of the latter, utilizing the reinforcing rails as guides during the driving of the rods into the rails on said bottom and when driving the rails of the top upon said rods, and then positioning said reinforcing rails substantially centrally of the walls of the coop, and then securing corner posts to the ends of the top and bottom rails.

7. In a method of assembling a poultry coop of that type including a bottom having its upper face provided with side and end rails and a top having side and end rails, said rails having spaced means for receiving wall forming rods, driving wall forming rods into said means of the rails on said bottom to form the side and end rails of the coop, disconnecting the end rails of the top from the side rails of the latter, successively driving the side rails of the top upon the rods forming the side walls, successively driving the top end rails upon the rods forming the end walls of the coop while such rods are sprung outwardly, and then connecting the top end rails to the top side rails.

8. In a method of assembling a poultry coop of that type including a bottom having its upper face provided with side and end rails and a top having side and end rails, said rails having spaced means for receiving wall forming rods, driving wall forming rods into said means of the rails on said bottom to form the side and end rails of the coop, disconnecting the end rails of the top from the side rails of the latter, successively driving the side rails of the top upon the rods forming the side walls, successively driving the top end rails upon the rods forming the end walls of the coop while such rods are sprung outwardly, and then connecting the top end rails to the top side rails.

end walls of the coop while such rods are sprung outwardly, and then connecting the top end rails to the top side rails, and then securing corner posts to the ends of said top and bottom rails.

6 In testimony whereof, I affix my signature hereto.

OSE F. CARPENTER.
